HOCKEY COASTER

Filed April 3, 1924

INVENTOR
Henry Riefschnider

Harry Bowen
ATTORNEY

UNITED STATES PATENT OFFICE.

HENRY RIEFSCHNIDER, OF SEATTLE, WASHINGTON.

HOCKEY COASTER.

Application filed April 3, 1924. Serial No. 703,870.

The invention is a toy that may be used as a coaster by a child wearing roller skates.

One object of the invention is to provide a device whereby a person with roller skates 5 may coast down a hill.

Another object of the invention is to provide a device which may be used as a coaster by a person wearing roller skates which is equipped with a brake.

10 And a further object of the invention is to provide a roller skate coaster that may also be used to play hockey.

With these ends in view the invention embodies a hockey stick having wheels on the 15 end of the handle, brakes for the wheels, a saddle, and a folding bar that may be placed across the knees.

Other features and advantages of the invention will be seen from the following description taken in connection with the drawings, wherein:—

Figure 1 is a side view of the device.

Figure 2 is a plan showing the saddle and knee bar.

25 Figure 3 is an end showing the arrangement of the wheels.

In the drawings I have shown my device as it would be constructed wherein numeral 1 indicates the hockey stick, numeral 2 the 30 wheels, and numeral 3 the saddle.

The stick 1 is provided with a bearing 4 at the end thereof in which the rollers 5 and 6 are rotatably mounted through a shaft 7. Above the wheels are brake shoes 8 and 9 35 which are mounted on a bar 10 which is pivotally attached to the under side of the stick 1 by bearings 11 and 12. The central portion of the bar 10 is bent downward to form an eye 13 as shown in Figure 1 so that a spring 14 which will pass through an opening 15 in the bearing 4 may be attached to it. The opposite end of the spring 40 may be attached to a hook 16 on the under side of the stick 1. The sides of the stick 1 may be reinforced at this point by cleats 45 17 and 18 as shown.

The saddle 3 which may be formed of sheet metal or any other suitable material 50 may be attached to the upper side of the stick 1 as shown in Figure 1 or in any suitable manner, as, for instance, that shown in Figure 1. In the design shown braces 19 and 20 are stamped from openings see Figure

2 in the saddle and bent downward so that they may be riveted or bolted to the stick. 55

A short distance above the saddle is a brake lever 21 which may be pivotally mounted between a cleat 22 and the side of the stick 1 on a pin 23 as shown in Figures 1 and 2, and another cleat 24 may be placed on the opposite side of the stick 1 to reinforce the stick. The lower end of the lever 21 which will project below the stick is provided with a hole 25 by which it may be connected by a wire 26 to the eye 13 in the bar 10. The wire 26 will pass on the under side of the stick and may be held in place by eyes 27 or any other suitable means. It will be seen that as the lever 21 is pulled upward it will draw upward on the wire and 60 force the brake shoes 8 and 9 downward on the wheels or rollers in order to retard the device.

On the under side of the stick is a bar 28 which is pivotally mounted on a bolt 29 which is provided with a thumb nut so that it may be held in a longitudinal or transverse position, and curved as shown as in Figure 2 so that it may be placed over the knees when a person is sitting on the saddle 3 and coasting. This will make it possible to hold the device and at the same time guide it without using the hands. It will be seen that this bar 28 may be twisted to a position under the stick so that it will be 75 parallel with it when it is not being used as a coaster or when it is being used as a 80 hockey stick.

It will be understood that changes may be made in the construction without departing from the spirit of the invention.

The construction will be readily understood from the foregoing description. To use the device as a coaster it may be held in the position shown in Figure 1 so that a person may sit on the saddle and place their feet, upon which are roller skates or the like, upon the ground. The bar 28 may then be opened to the position shown and placed upon the knees. It will be seen that the 90 progress of the device may be retarded as much as desired by applying the brakes through the lever 21. When the device is used for playing hockey the bar 28 may be 95 twisted to a position parallel to the stick 100 and the stick may be gripped at any convenient 105

ient point adjacent the saddle or upper end so that the large end of the stick may be swung with perfect freedom.

Having thus fully described the invention, 5 what I claim as new and desire to secure by Letters Patent, is:—

In a hockey coaster of the class described, a hockey stick substantially held in an in-

verted position, rollers at the lower end of the stick, a saddle upon the said stick and a transverse bar mounted in such a position that it may rest upon the knees of a person sitting upon the saddle, said transverse bar being readily adjustable to a longitudinal position.

HENRY RIEFSCHNIDER.
